UNITED STATES PATENT OFFICE.

SYLVANIS B. NICKUM, OF MARION, INDIANA.

RAILROAD-SWITCH.

SPECIFICATION forming part of Letters Patent No. 269,811, dated December 19, 1882.

Application filed November 29, 1881. (No model.)

To all whom it may concern:

Be it known that I, SYLVANIS B. NICKUM, of the town of Marion, county of Grant, and State of Indiana, have invented certain new and useful Improvements in Railroad-Switches, of which the following is a specification.

My said invention consists of apparatus whereby an air-pump or such similar device may be manipulated to operate a railway switch or switches, as will be hereinafter specifically described.

Referring to the accompanying drawings, which are made a part hereof, and on which similar letters of reference indicate similar parts, Figure 1 is a perspective view of a section of double railway-track, with a switch in each track, and provided with my improved apparatus; Fig. 2, a plan view of so much of the track as is necessary to show one of the switches and that portion of the apparatus which directly operates the same; Fig. 3, a transverse vertical section of the track and accompanying apparatus on the dotted line x - x , Fig. 2, near the point of the switch; Fig. 4, a similar view to Fig. 3, except that the parts are operated so that the switch is in a different position; Fig. 5, a sectional view of the operating mechanism forming part of my invention and its immediate connections, and Fig. 6 a detail view of the switch-lock.

In said drawings, the portions marked A represent the ordinary railroad-rails; B B', the movable rails of the switches; C, the frogs; D, non-movable switch-rails connecting the frogs to the rails A; E, cylinders alongside the track, at or near the points of the switch-rails; F' F² F³ F⁴ F⁵, pipes leading from said cylinders to a pipe, F, connected with an air pump or compressor; G, said pump or compressor; H, a steam or water engine cylinder connected with said air-pump; I, a piston-rod, preferably extending from said pump to said engine, and carrying piston-heads for both; and J, a lever by which the valves connected with this invention are operated.

In connection with this invention I prefer to use that character of switch wherein the switch-rails come to an edge and rest closely against the sides of the track-rails, as shown in the drawings, though it is applicable as well

to the older and more common form, where the switch-rails and track-rails abut.

The switch-rails B B' are connected by bars b, as usual, and are operated by an attachment from the operating parts to the one of 55 said bars nearest the points of the rails.

The cylinder E contains a piston, E', the rod of which is connected to the bar b, (preferably by a sliding joint, as shown in Figs. 3 and 4,) and as said piston is forced back and forth by 60 the compression or exhaustion of air in said cylinder the movable switch-rails are operated, and the switch is thereby opened or closed. As before stated, the connection between the piston-rod and the tie-bar of the 65 switch is preferably a sliding joint. A satisfactory joint of this character is formed by providing upon the under side of said bar a downwardly-projecting lug, b², which has an opening through which said piston-rod may slide, 70 and providing said piston-rod on each side of said lug with collars or projections e, which will not pass through the opening in said lug, thereby defining the distance which said piston-rod may move independently of said bar, 75 it being desirable that such a movement should be permitted for purposes which will now be explained. A pawl or catch, E², is secured by a pivot, e², to the cross-tie of the railroad, or to some other substantially-immovable part, in 80 such relation to the tie-bar b that it will engage with a notch or projection, b', thereon, and when so engaged will hold said tie-bar and the switch-rails thereon firmly in position, which is of course important, as it prevents the possibility of the jarring of passing trains displacing the switch. It is also important that said catch be disengaged automatically when the apparatus is operated to set the switch to the siding. This is done by means of a notch in 85 the piston-rod E', into which the other end of the pawl E² enters, it being forced therein by a spring, as shown in Fig. 6, and where it rests when the switch is set to the main. When the switch is being set to the siding the first operation moves the piston-rod without moving the switch until the collar thereon nearest the piston strikes the lug on the tie-bar, by which time the notch in said piston-rod has moved 90 out from under the pawl E², forcing the latter 95 to disengage from the notch in the piston-rod, forcing the latter 100

up into a substantially-horizontal position and freeing the engagement between it and the tie-bar, whereby the piston-rod, in continuing its movement, is enabled to force the tie-bar and 5 switch-rails to their proper position.

The pipes F' , F'' , &c., are branches of the pipe F , which leads to the cylinder of the air pump or compressor G , and each conducts the air, water, steam, or gas which operates the 10 piston E' to one of the cylinders E , and is opened and closed by a cock or valve, f .

The cylinder G is provided with a valve, g , for the admission of air, which is operated by the rod g' , which is in turn operated by the 15 lever J . It is also provided with an open vent, g'' , behind the piston-head G' therein. The operation of this piston-head, as will be readily understood, compresses the air in the pipes F , F' , &c., and cylinders E as it moves forward, 20 and exhausts it as it moves backward, the supply being kept up through the valve g .

The cylinder H and the valves and other connections shown are simply the parts of an ordinary steam or water engine, and are shown 25 as a convenient and desirable means of furnishing power to operate my invention.

The piston-rod I extends into both the cylinder H and the cylinder G , and carries the piston-heads H' and G' upon its ends respectively, and the movement of said heads is thus rendered coincidental.

The lever J is pivoted at j to some stationary portion of the device, and has pivoted thereto at j' the rod g' , which connects with 35 the valve g , and at j'' the rod h' , which connects with the valve h , and said valves are thereby enabled to be operated by means of said lever.

The operation of my invention may be recapitulated as follows: The steam, air, or water enters through the pipe H'' and operates upon the head H' in the usual manner, and, the valve g being closed, operates the head G' to compress the air into the pipe F and whichever of its branches is open, and thus, through 40 the cylinder E and piston E' , pushes the switch-rails into the position shown in Fig. 4. When this operation is reversed and the piston forced back to the position shown in the drawings

the air in the pipes and cylinders is so far exhausted as to draw the switch-rails back into 50 the position shown in Fig. 3.

It may be well to remark that the valves g and h are secured to the lever J in such relation that when one is open the other is always closed. This is so that when the apparatus is 55 at rest there will be free communication between the inside of the cylinder G and the outer air, and when the apparatus is being operated that such communication shall be interrupted. 60

As will be understood in reading the foregoing specification, I prefer to use atmospheric air to operate the switches, although I do not confine myself to it. Any motive power may be used that is convenient or desirable, the 65 steam or water engine shown forming no part of my invention.

I am aware of the Patent No. 188,851, of March 27, 1877, in which a toggle-joint is used as a locking means, and such construction is 70 not sought to be covered in this application.

Having thus fully described my said invention, what I claim as new, and desire to secure by Letters Patent, is—

1. In a railroad-switch adapted to be operated by fluid-pressure, the combination of the switch-rails, the tie-bar b , having rigid perforated lug b^2 and lug b' , the piston-rod adapted to slide, to a limited extent, through said lug b^2 , the pivoted catch E^2 , and the spring resting 80 thereon, the whole adapted to serve as a switch-lock, substantially as set forth. 75

2. The combination, in a railroad-switch-operating mechanism, of a cylinder adapted for the reception of steam or water, and an air-compressing cylinder operated by the rod of the steam or water cylinder, and a pipe for conducting the compressed air to a series of branch pipes, substantially as set forth. 85

In witness whereof I have hereunto set my 90 hand and seal, at Indianapolis, Indiana, this 25th day of November, A. D. 1881.

SYLVANIS B. NICKUM. [L. s.]

In presence of—

C. BRADFORD,
CHAS. L. THURBER.
